Attorney

UNITED STATES PATENT OFFICE

ROY KIRBY, OF WENATCHEE, WASHINGTON

SPOKE TIGHTENER

Application filed October 23, 1928. Serial No. 314,376.

The present invention relates to a spoke tightener for wheels and has for its prime object to provide a device of this nature possessed of an exceedingly simple structure 5 that is strong and durable, easy to manipulate, compact and convenient, and thoroughly efficient and reliable in operation.

With the above and numerous other objects in view, as will be apparent as the description proceeds, the invention resides in certain novel features of construction, and in the combination and arrangement of parts as will be hereinafter more fully described and claimed.

15 In the drawing:

Figure 1 is an end elevation of the apparatus embodying the features of my invention, showing a wheel engaged therein, a portion of the felly of the wheel being shown 20 in section.

Figure 2 is a side elevation of the apparatus.

Figure 3 is a top plan view thereof.

Figure 4 is an enlarged detail section, 25 taken substantially on the line 4-4 of Figure 2, and

Figure 5 is an elevation of another embodiment of the invention.

Referring to the drawings in detail, and 30 first to Figures 1 to 4 inclusive, it will be seen that numerals 5 denote a pair of spaced parallel co-extensive base bars held in such relationship by bolts 6 and 7, having spacer sleeves 8 thereon. From each base bar 5 there rises an end standard 10, and an end standard 11, and an intermediate standard 12. Bars 14 are formed on the upper ends of the standards 10 and 12 and extend in coextensive spaced parallel relationship to 35 each other, terminating in jaws 15 for straddling a spoke as is clearly indicated in Figure 1. A lever 16 is pivotally mounted, intermediate its ends between upper portions of the standards 10 by means of a bolt 17, 40 and at one end is formed with a head 18 to engage the outer extremity of the spoke straddled by the jaws 15. At the other end, the lever 16 is provided with a rack quadrant 19, meshing with a pinion 20, formed integral with a gear 21, rotatable on a bolt 22,

between intermediate portions of the standards 12. A bolt 23 extends between the upper extremities of the standards 11 and has rockable thereon a lever 24, with which is pivotally engaged a pawl 25 for engaging the gear 21. A pawl 26 is rockable on the bolt 23, for engaging the gear 20. Thus the gears are free to rotate in one direction by action of the actuating pawl 25 and the holding pawl 26, when the lever 24 is rocked, 55 and thus by rocking this lever, the head and the jaws may be clamped against opposite sides of the felly of the wheel with a spoke between the jaws engaged by the head 18 for tightening the spoke. 60

In Figure 5 I have shown another embodiment of the invention including a base bar, 30 having one end inclined upwardly at an obtuse angle thereon as is indicated at 31, and terminating in a jaw 32. A lever 33 is 70 rockable by the bolt 34, on the extension 31, and has a head 35 at one end for cooperating with the jaw 32. A standard 36 is fixed, as at 37, to the bar 30, to rise therefrom, and this standard is free to rock. A link 38 is 75 rockably mounted, as at 39, on the upper end of the standard 36, and pivotally engaged as at 40 with the lever 33. An operating lever 41 is pivotally mounted intermediate its ends as at 42, on the upper end of the standard 80 43, engaged on the bar 30 as at 44, and rocking upwardly therefrom. Obviously, by rocking the lever 41 the link 38 is rocked to rock the lever 33 and move the head 35 toward the jaw 32. 85

It is thought that the construction, operation, utility, and advantages of this invention will now be quite apparent to those skilled in this art, without a more detailed description thereof. The present embodiments of this invention have been disclosed in detail, merely for the purposes of exemplification, since in actual practice they attain the features of advantage enumerated as desirable in the statement of the invention 90 and the above description.

It will be apparent that changes in the details of construction, and in the combination and arrangement of parts may be resorted to, without departing from the spirit 100

or scope of the invention as hereinafter claimed or sacrificing any of its advantages.

Having thus described my invention, what I claim as new is:

- 5 An apparatus of the class described including a pair of spaced parallel co-extensive base bars, each bar having standards rising from the ends thereof, and a standard rising from the intermediate portion thereof, a bar
- 10 secured to the upper end of one outer standard, and the intermediate standard of each bar and adapted to project beyond the end standard to provide a jaw, a relatively small and a relatively large combined gear structure
- 15 rotatably mounted between the intermediate standards, a lever pivotally mounted between the end standards last mentioned and having a quadrant rack on one end to engage with one of the gear portions, and
- 20 a head on the other for cooperation with the aforementioned jaw, a lever pivotally mounted between the upper ends of the other end standards and having a pawl to engage the larger gear portion, and an additional
- 25 pawl rockably mounted on the last mentioned end standard to engage the smaller gear portion.

In testimony whereof I affix my signature.

ROY KIRBY.
